CONNECTOR FOR REUSABLE PRESSURE-RESISTANT BLASTING CARTRIDGES

Michael M. Lilly, Charleston, W. Va., and James P. Swed, Gibbstown, N. J., assignors to E. I. du Pont de Nemours and Company, Wilmington, Del., a corporation of Delaware

Application February 18, 1953, Serial No. 337,462

3 Claims. (Cl. 102—24)

1

The present invention relates to an improved assembly for providing electrical connection from a source of electrical energy to a blasting cartridge of the reusable, pressure-resistant tube type.

The use of reusable pressure-resistant tube blasting cartridge in mining operations is rapidly gaining wide acceptance. Essentially, the blasting cartridges consist of a heavy steel tubular body closed at one end with a firing head and at the other end with a pressure-responsive discharge head. The firing head contains a centrally positioned electrode which extends into the tubular body and is insulated from the remainder of the blasting cartridge. The discharge head contains a number of venting apertures, usually sloping outwardly toward the firing head end of the cartridge, and valving means or a rupturable disc which will permit the sudden release of gases under high pressure from within the tube. The tube body contains the gas-producing charge, which may be a substance capable of decomposing into gaseous material upon initiation, or may be a liquefied or solidified form of a normally gaseous material. A typical charge of the former type contains a large proportion of ammonium nitrate, and is initiated by means of an electrical heating element imbedded within the charge. A typical example of the latter type substance is carbon dioxide solidified or liquefied under pressure and gasified by the heat produced by the action of an exothermic starter mixture or by an electrical resistance coil. The starter mixture is initiated by means of an electric squib or an electric heating element.

In use, the charged blasting tube is loaded into a borehole after lead wires have been connected to the firing head, and initiated by the application of current through the lead wires. Due to the shattering action of the suddenly released gases, the entire assembly is frequently buried under a mass of broken fragments. Since the fragments have sharp edges and strike the assembly with considerable force, the lead wires are naturally subjected to severe abuse. Attempts have been made to provide permanent connections where the lead wires were heavily shielded and firmly secured to the firing head. This assembly is both costly to produce and difficult to repair. Another practice has been to use expendable wire at the portion near the tube. The disadvantages of this practice are the time required for repeated connections, the loss of wire, and the contamination of the material being blasted.

2

It is an object of the present invention to provide an improved assembly for making electrical connection with the firing head of a pressure-resistant blasting tube. A further object is to provide an assembly for making electrical connection with the firing head of a pressure-resistant blasting tube wherein the lead wires will not be damaged by fragments resulting from the blasting action. Additional objects will become apparent as the invention is further described.

We have found that the foregoing objects may be attained when we provide a socket on the firing head end of a pressure-resistant blasting cartridge, and a plug of such size as to form tight 15 friction fit with the said socket firmly attached to the lead wires. The socket is centrally positioned at the outside end of the firing head and the insulated electrode within the firing head projects centrally into the space created by the 20 socket. The plug is of greater length than the depth of the socket and is preferably molded about the end of a pair of heavily insulated lead-in wires. The end of the plug opposite the wire, i. e., the end of the plug which is inserted into 25 the socket, has a peripheral metal sleeve which is connected to one of the lead-in wires, and a transverse slot containing a metal liner connected to the other lead-in wire. The liner is shorter than the diameter of the plug so that it is not 30 in contact with the sleeve which is also slotted at the same points. When the plug is inserted into the socket, the sleeve is in contact with the sides of the socket and the liner is in contact with the electrode, thus providing the desired electrical 35 contacts.

In order to more fully describe the present invention, reference is made to the accompanying drawings, in which:

Figure 1 represents a plan view of the blasting 40 assembly in accordance with the present invention;

Figure 2 represents a partially sectional view of the assembly;

Figure 3 represents a view of the plug from the 45 contact end; and

Figure 4 represents a view of the plug from the side.

Referring to the figures in greater detail, 1 is a tube body, generally of steel, of the pressure-resistant cartridge, 2 is the discharge head which contains the pressure-responsive release mechanism and the venting ports, 3 is the firing head, 4 is the plug at the end of the insulated lead-in wires, 5, 6, and 7 representing the individual 50 lead-in wire cores. 8 is a U-shaped metal liner

inserted in slot 10 transversely across plug 4. 9 is a metal sleeve surrounding the slotted end of plug 4, being itself slotted in alignment with slot 10. 11 is an electrode inside and insulated from firing head 3 by insulators 12, the latter being retained in position by element 13.

As is shown in the drawings, lead-in wire core 6 is welded to sleeve 9 while lead-in wire core 7 is welded to line 8. When the plug is in the position shown in Figure 2, the sleeve 9 forms electrical contact with the firing head 3 and liner 8 forms electrical contact with the electrode 11. In the preferred form of the invention, sleeve 9 will be forced inwardly on plug 4 by the insertion in the socket in firing head 3, and liner 8 will be expanded by the entrance of electrode 11, so that the plug 4 will be under compression, thus assuring retention of the plug 4 in the socket during the insertion of the assembly into a borehole, and also better electrical contact with the firing head 3 and the electrode 11.

The assembly of the plug and blasting cartridge are secured together only by the friction fit. Thus, when the cartridge is initiated within a borehole an initial stream of gases issue through the space between the borehole and the cartridge outwardly at tremendous velocity. These gases have sufficient drag on the plug and lead-in wire to detach the plug from the firing head and blow it completely free from the fall of the material being blasted. The slot 10 permits shaking out any dirt and facilitates cleaning liner 8 to insure a good contacting surface, so that the plug assembly is ready for reuse by simply inserting into the firing-head socket of a charged blasting cartridge.

The plug is preferably molded directly onto the length of heavily insulated lead-in wires,

but clamp or screw connections may be used. Natural or synthetic rubber is the preferred resilient material of a non-conductive nature for fabrication of the plug, but materials such as synthetic polymers having the desired resilience may also be used. Accordingly, we intend to be limited only by the following claims:

We claim:

1. An improved blasting assembly of a reusable blasting cartridge of the type described herein and a detachable lead-in wire device adapted to be blown free and clear of the fall of blasted material by the discharge within a borehole of said cartridge which comprises a firing head at the initiation end of the cartridge containing a central cylindrical socket at the outside end thereof, an insulated electrode in axial alignment with said firing head and having one end projecting into said socket, and a cylindrical plug of a resilient non-conductive material, a portion thereof being inserted in said socket, said portion having a metal sleeve about the periphery in contact with said firing head, a transverse slot across the end of said plug and sleeve containing a centrally positioned metal liner of shorter length than the diameter of the plug in contact with said electrode, said plug being secured to two insulated lead-in wires, one of which is connected to said metal sleeve and the other to said metal liner, said plug and sleeve forming a tight fit with said socket.

2. An assembly as claimed in claim 1, wherein the sleeve has a normal outside diameter slightly larger than the diameter of said socket.

3. An assembly as claimed in claim 1, wherein the plug is molded to the insulated lead-in wires.
